UNITED STATES PATENT OFFICE.

BERTHA E. TEDSTONE, OF SAN ANTONIO, TEXAS.

DRESS SHIELD.

Application filed October 19, 1926. Serial No. 142,675.

This invention relates to new and useful improvements in apparel, and particularly shields for dresses.

Ordinarily the dress shields, now in use, are sewed into the arm-holes of dresses, and when said shields become odorous, it is necessary to remove them, by cutting the stitching. Then, when the shields have been cleaned, they are resewed into the dresses. This requires considerable time and labor, especially if the shields are to be shifted from one dress to another.

It is therefore the principal object of the present invention to provide a dress shield such as may be easily and quickly secured within the arm-hole of a dress, and as quickly removed therefrom, and placed in another dress.

Another object is to provide novel means for detachably securing the shields in a dress by means of which the shields may be adjusted toward and away from the arm-pits, or forwardly or rearwardly therebeneath, as the case requires.

Other objects and advantages will be apparent from the following description when taken in connection with the accompanying drawing.

In the drawing:

Figure 1 is a perspective view, looking into the interior of the arm-hole of a dress, showing one of the dress shields in place therein.

Figure 2 is a vertical sectional view on the line 2—2 of Figure 1.

Figure 3 is a perspective view of the shield removed from the dress, with a portion folded back.

Referring particularly to the accompanying drawing, 10 represents a portion of a dress surrounding the arm-hole, and 11 a portion of the sleeve, the former having the seam 12, and the latter the longitudinal seam 13, the sleeve being connected to the dress, at the arm-hole, by the seam 13'.

Secured to the dress seam 12, and extending downwardly from a point adjacent the lower side of the arm-hole, is a tape strip 14, said strip being secured along one edge and being formed with a longitudinal series of longitudinally extending openings 15. Secured in a similar manner to the longitudinal seam 13, of the sleeve 11, is a similar tape 16, having the elongated openings 17 formed therein. Secured to the forward and rear sides of the arm-hole, in the seam

13', thereof, are the tape strips 18, each having the elongated openings 19 formed therein.

The shield, shown in detail in Figure 3, 60 comprises the two crescent-shaped waterproof sheets 20 and 21 secured along their inwardly curved edges. Secured to each end of the attached portions of the sheets 20 and 21 is a short length of tape 22, that portion 65 which is free being provided with the socket portion 23 of a snap fastener, the head 24 being sewed to the shield, near the other end of the tape. Secured to the inner faces of the rear edge portions of the sheets 70 20 and 21 are the head portions 25 of snap fasteners, the socket portions 26 being carried by the free ends of the tapes 27, which are secured to the same faces of the sheets 75 at points slightly nearer the lower edges thereof.

In securing the shield in place the sheets 20 and 21 are disposed in straddling relation to the lower portion of the arm-hole seam, so that one sheet lies within the sleeve, 80 below the arm-hole, while the other sheet lies within the dress, beneath the arm-hole. The tapes 27 are passed through appropriate openings of the tapes 14 and 16 and the portions of the snap fasteners properly engaged 85 so that the points or lower portions of the sheets are held in place. The tapes 22 are then inserted in appropriate openings of the tapes 18, and the snap fasteners thereof engaged to hold the upper portion of the shield 90 in proper position.

If it is desired to move the shield forwardly or rearwardly, in the arm-hole, the tapes 22 are adjusted into openings of the tapes 18, at different positions from which 95 they were originally secured. Also, the entire shield may be raised in the arm-hole, by engaging the tapes 22 in openings 19 at higher levels.

From the above, it will readily be seen 100 that, with different dresses equipped with the tapes 14, 16, and 18, a single pair of shields may be quickly shifted from one dress to another, in a short time. Furthermore, it will be appreciated that, when the shields 105 have become odorous from perspiration, they may be removed at night, washed, and hung up to dry, so that they may be readily restored to the dress in the morning, without waste of time or labor.

It will be noted that the shield is placed in the arm-hole in such position that the fas-

tener portions 25 are directed toward the rear, thereby facilitating the inserting of the tapes 27. These tapes 27 are of sufficient length to permit the before-mentioned adjustment of the shield, without the necessity of separating the fasteners 25-26.

What is claimed is:

1. The combination with the arm-hole portions of a dress and sleeve, of a dress shield disposed in the arm-hole and having flaps, apertured members carried by the seams of the dress and sleeve, means on the ends of the shield removably engaged in the apertured members of the sleeve seam, and means 10 on the lower edges of the flaps of the shield for detachable engagement in the apertured members of the dress seam.

2. The combination with the arm-hole portions of a dress and sleeve, of apertured 20 members secured in the walls of the arm-

hole, apertured members secured in the dress and sleeve, a shield disposed within the arm-hole, and tapes carried by the shield and detachably engaged through the apertured members.

3. The combination with the arm-hole seam, the sleeve seam, and the side seam of a dress, of tapes secured within the said seams and having longitudinal series of openings, and a dress shield having tapes 30 secured to the ends of the upper edge thereof engaged through the openings of the tapes of the arm-hole seam, said dress shield having flaps, and tapes carried by the lower edges of the flaps of the shield and engaged 35 through the openings of the tapes of the sleeve and dress seams.

In testimony whereof, I affix my signature.

BERTHA E. TEDSTONE.
